United States Patent [19]

Cronström et al.

[11] Patent Number: Des. 298,122

[45] Date of Patent: ** Oct. 18, 1988

[54] SOCKET FOR LIGHT EMITTING DIODE

[76] Inventors: Michael Cronström; Michael Sällberg, both of P.O. Box 5209, S-102 45 Stockholm, Sweden

[**] Term: 14 Years

[21] Appl. No.: 742,759

[22] Filed: Jun. 10, 1985

[52] U.S. Cl. D13/25; D13/28

[57] CLAIM

The ornamental design for a socket for light emitting diode, as shown and described.

DESCRIPTION

FIG. 1 is a bottom perspective view of the socket for a light emitting diode showing our new design;

FIG. 2 is a top plan view thereof;

FIG. 3 is a bottom plan view thereof; and

FIG. 4 is a side elevational view thereof, and all sides being identical.

FIG. 4

FIG. 3

FIG. 2

FIG. 1
